(57) **CLAIM**

The ornamental design for a core for rotary electric machine, as shown and described.

DESCRIPTION

FIG. 1 is a perspective view of a first embodiment of a core for rotary electric machine showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a cross-sectional view thereof taken along the line 8-8 in FIG. 6;

FIG. 9 is a perspective view of usage;

FIG. 10 is a perspective view of a second embodiment of a core for rotary electric machine showing our new design;

FIG. 11 is a front view thereof;

FIG. 12 is a rear view thereof;

FIG. 13 is a left side view thereof;

FIG. 14 is a right side view thereof;

FIG. 15 is a top view thereof;

FIG. 16 is a bottom view thereof;

FIG. 17 is a cross-sectional view thereof taken along the line 17-17 in FIG. 15; and,

FIG. 18 is a perspective view of usage.

The broken lines in the figures are included for the purpose of illustrating the unclaimed portions of the core for rotary electric machine and form no part of the claimed design. The dot-dash lines define the bounds of the claimed design and form no part thereof.
